UNITED STATES PATENT OFFICE.

EDGAR AMOS SWEET, OF PEACEDALE, RHODE ISLAND.

EXPLOSIVE FIRE-ALARM BUTTON.

SPECIFICATION forming part of Letters Patent No. 788,225, dated April 25, 1905.

Application filed August 26, 1904. Serial No. 222,345.

To all whom it may concern:

Be it known that I, EDGAR AMOS SWEET, a citizen of the United States, residing at Peace-
dale, in the county of Washington and State
5 of Rhode Island, have invented certain new
and useful Improvements in Explosive Fire-
Alarm Buttons, of which the following is a
specification.

This invention is a fire-alarm of the general
10 size and shape of a button charged with an ex-
plosive and provided with one or more fuses
which project laterally outward in position to
be ignited by a flame. The device is provided
with a rearwardly-projecting spur by which it
15 may be readily secured to the walls, wall dec-
orations, ceiling, or floor of a room with the
fuses in proximity to the surface in position
to give instant warning of the presence of fire.

In its preferred form the alarm consists of
20 a shallow metal cup with spaced lateral open-
ings near its base, a separate packet of an ex-
plosive in the base of the cup with integral
flat fuses which extend through the openings,
25 and a layer of plaster-of-paris overlying and
confining the explosive.

Referring to the accompanying drawings,
Figure 1 is a front elevation, and Fig. 2 is a
vertical axial section, of the preferred form
30 of fire-alarm; and Fig. 3 is a front elevation,
and Fig. 4 is a vertical axial section, of a
modified form of fire-alarm.

The alarm shown in Figs. 1 and 2 comprises
a shallow receptacle 1, preferably stamped out
of tin-plate. A spur 2, shown as the point of
35 an ordinary tack, projects rearwardly from
the back of the cup, the head of the tack be-
ing soldered thereto. A charge 3 of an ex-
plosive, such as gunpowder or guncotton, is
held in a thin paper container which has
40 short integral radial flat extensions 4, also
filled with an explosive and constituting fuses.
These fuses, shown as four in number, pro-
ject through lateral openings in the sides of
45 the cup 1 near its base in position to lie sub-
stantially on the surface of the object to
which the alarm is attached. A disk 5 of
paraffined cardboard is forced into the cup
upon the explosive, and the cup is then filled
with a layer 6 of plastic material, such as

plaster-of-paris, which is held in place by the 50
inwardly-bent edge 7 of the cup.

The alarm shown in Figs. 3 and 4 also com-
prises a shallow sheet-metal cup 1', having
the head of a tack 2 soldered to its back, and
an explosive charge 3, having fuses 4, which 55
project through lateral openings near the base
of the cup. In this instance, however, the
charge is confined by a felt wad 8, which is
held in place by a sheet-metal cap 9, having
60 slots 10, which receive the fuses, and a flanged
edge 11, which is bent underneath the back
of the cup.

It will be seen that this alarm is simple,
neat, and inexpensive. It can be attached to
the surface of a room or its furniture, with 65
its fuses in proximity thereto, and while it is
unobtrusive and of small size it contains a
sufficient charge of explosive to give warning
to persons in distant parts of the building.
It can be manufactured in various sizes and 70
shapes and in assorted colors to match the ob-
ject to which it is attached.

I claim—

1. An explosive fire-alarm button, comprising
a shallow receptacle having lateral open- 75
ings at various points around its periphery,
an explosive charge in said receptacle, integral
fuses extending from said charge through
said lateral openings, and means for confining
80 said charge, as set forth.

2. An explosive fire-alarm button, comprising
a shallow receptacle having a spur project-
ing from its back and a lateral opening or 85
openings, a separate packet of an explosive
in said receptacle having an integral fuse or
fuses extending through said lateral opening
or openings, and means for confining said ex-
plosive, as set forth.

3. An explosive fire-alarm button, comprising
a shallow receptacle having lateral open- 90
ings at various points around its periphery,
an explosive charge in said receptacle, a paper
charge-container having integral fuses extend-
ing through said lateral openings, and means
for confining said charge, as set forth. 95

4. An explosive fire-alarm button, comprising
a shallow receptacle having attaching
means at its back and lateral openings at vari-

ous points around its periphery, an explosive charge in said receptacle, fuses extending from said charge through said lateral openings, and an easily frangible confiner for said 5 charge, as set forth.

5. An explosive fire-alarm button, comprising a shallow receptacle having a spur projecting from its back and a lateral opening or 10 openings, a separate packet of an explosive in said receptacle having an integral fuse or

fuses extending through said lateral opening or openings, and a layer of a plastic composition confining said charge, as set forth.

In testimony whereof I affix my signature in presence of two witnesses.

EDGAR AMOS SWEET.
